Primary Examiner — Brett Miller*Assistant Examiner* — Mary Anne Arntzen(74) *Attorney, Agent, or Firm* — Womble Bond Dickinson (US) LLP(57) **CLAIM**

The ornamental design for a watch, as shown and described.

DESCRIPTION

FIG. 1 is a front view of a watch showing the new design; and,

FIG. 2 is a front, right, and top perspective view thereof. The dash-dot lines in the drawings show elements that form no part of the claimed design.

1 Claim, 2 Drawing Sheets(56)
